MARINE CAGE

Application filed February 12, 1929. Serial No. 339,347.

Marine piling of different characters such as wood, metal, or concrete will deteriorate after they have been placed in the water due to the action of the water, or to sea growth 5 or sea animals, so that it is necessary to repair them in some way. As an example, I will use concrete piling about which it is necessary to place a sheath or coating of concrete or cement to further strengthen and 10 reinforce the same. The repairs to the pile extend from a few feet below the low water line to about the high water line and heretofore the difficulty has been to reach the piling below the water and effectively work 15 upon this area.

An object of my invention is to provide a marine cage which can be placed around the piling and partly submerged so that the affected area of the piling can be reached and 20 worked.

Another object is to provide a marine cage which can be quickly and easily emptied of water after it is in position and can be kept dry while the workmen are working on 25 the pile.

Still another object is to provide a marine cage which can be effectively held partly submerged and this holding means also serves to seal off the water from the inside 30 of the cage.

Other objects, advantages, and features of invention may appear from the accompanying drawings, the subjoined, detailed description, and the appended claims.

35 In the drawings

Figure 1 is a longitudinal sectional view of my cage in position around a pile.

Figure 2 is an enlarged fragmentary vertical view of the lower end of the cage.

40 Figure 3 is a side elevation of the cage on a reduced scale.

Figure 4 is an enlarged fragmentary horizontal sectional view of the bottom of the cage.

45 Figure 5 is an enlarged horizontal sectional view of the door seal.

Figure 6 is an enlarged horizontal sectional view of the hinge seal.

50 Referring more particularly to the drawings, my cage comprises a metal housing 1

open at the top, the housing being of such diameter that workmen can readily be accommodated therein and may operate upon the pile 2 around which the cage is placed. A door 3 is provided in the side of the hous- 55 ing 1 and this door is hinged at 4.

A fibrous or rubber strip 5 is secured longitudinally of the hinge and one side of the strip 5 is secured to the housing 1 and the other to the door 3. Thus the hinge is effectively sealed against leakage. The swinging end of the door is provided with a flange 6, said flange being complementary to a flange 7 secured to the housing 1. A packing is secured between the two flanges and a plurality of bolts 9 extend through the flanges and hold the packing 8 in position. Thus the swinging end of the door is prevented from leaking.

A circular opening 10 is provided in the bottom of the housing 1 and centrally thereof and the piling 2 extends through this opening. A bottom door 11 extends from the central opening 10 to the outer periphery of the housing 1 and this door is also provided with a packed hinge 12 and a sealed swinging end 13 of the same character as previously described for the door 3. The marine cage is placed around the piling by opening the doors 3, 11, inserting the piling 60 through these doors, and then closing and bolting both of the doors.

In order that the cage may be applicable to various sizes of piling the opening 10 is made larger than the piling and a plate 14 65 is dropped over the piling and fits closely about the same, this plate serving to close the opening 10. A plastic or cement seal 15 is then poured around the piling 2 and upon the plate 14, thus sealing the bottom of the 70 cage.

A displacement chamber 16 is provided in the bottom of the cage, the purpose of which will be further described. The inner walls of the chamber 16 taper outwardly, as shown 75 at 17, and these walls serve to confine the seal 15 and bear against said seal to prevent the cage from moving upwardly due to the buoyancy thereof after the water has been removed from the cage. A valve 18 is 80

provided in the bottom of the chamber 16 and a second valve 19 is provided in the top of the chamber, the last named valve opening into the housing 1. A pipe 20 rises from the pipe 19 and an operating handle 21 is pivotally secured to the top of the pipe. A rod 22 rises from the valve 18 and extends upwardly through the pipe 20. An operating handle 23 is secured to the top of the rod 22.

Water is removed from the inside of the cage in the following manner: The valve 18 is closed and the valve 19 is opened, thus permitting water to drain from the inside of the cage into the displacement chamber 16. The valve 19 is now closed and the valve 18 opened. Air under pressure is introduced into the tube 20 through the pipe 24, the air passing downwardly through the tube and through the valve 19 displacing the water in the displacement chamber and forcing the water out past the valve 18. When the water is removed the valve 18 is again closed and the operation repeated.

For the purpose of more conveniently placing the seal 15 a grouting tube 25 rises from adjacent the top of the displacement chamber 16 and extends above the normal water level in the housing. A scaffolding 26 is provided approximately midway of the housing 1 upon which the workmen can stand to work upon the upper areas of the piling.

My cage is assembled around the pile before it is partially submerged, that is, the doors 3 and 11 are closed after which the cage is lowered to the required point, then in order to hold the cage in this position a plurality of stabilizing screws 27 are provided, said screws extending through blocks 28 which are secured to the top of the displacement chamber or upon the scaffolding 26. These screws engage the pile 2, as shown in Figure 1, and prevent the housing from moving upwardly while the seal 15 is being placed. After the seal is in position and has hardened the water is removed from the housing, as previously described, after which the workmen enter the cage and the work on the pile commences.

A plurality of hook bolts or lugs 29 are provided on the housing 1 for the purpose of transporting it from one pile to another. Outwardly curved wave deflecting sections 30 are provided at the top of the housing 1 for the purpose of deflecting a wave outwardly and keeping the water from coming over the top of the housing.

The arrangement of my displacement chamber is such that it can be easily operated at any time without inconveniencing the workmen in event there is a slight leakage into the cage, or it may be continuously operated if necessary. The buoyant effect of the housing is counteracted by the tapered

walls 17 bearing upon the cement seal 15, this seal being in vertical shear and is of sufficient strength to overcome the upward thrust.

Having described my invention, I claim:

1. A marine cage adapted to be placed around a pile and comprising a housing open at the top, said housing having an opening in the bottom thereof through which the pile extends, a door in the side of said housing, a second door in the bottom of the housing, the cage being adapted to be assembled around the pile through said doors, means to seal the bottom opening of the housing around the pile, and means whereby the water may be removed from within the housing.

2. A marine cage adapted to be placed around a pile and comprising a housing open at the top, said housing having an opening in the bottom thereof through which the pile extends, a door in the side of said housing, a second door in the bottom of the housing, the cage being adapted to be assembled around the pile through said doors, means to seal the bottom opening of the housing around the pile, a displacement chamber in the bottom of said housing, a valve in the bottom of said chamber, a second valve in the top of said chamber, air inlet means into said displacement chamber, and manually operated means connected to both of said valves.

3. A marine cage adapted to be partly submerged and assembled around a piling comprising a housing open at the top, said housing having an opening in the bottom thereof, through which the piling extends, a door in the side of said housing, a second door in the bottom of said housing, said last named door extending to the central opening in the housing, a displacement chamber in the bottom of said housing, sealing means in the bottom of the housing around the piling, valve means in the bottom of said displacement chamber, a second valve means in the top of said displacement chamber, means to actuate both of said valves, and air inlet means connected to said displacement chamber whereby the water may be removed therefrom.

4. A marine cage adapted to be partly submerged around a pile comprising a housing open at the top, a displacement chamber in the bottom of said housing, a door in the side of the housing, said housing having an opening in the bottom thereof, through which the piling extends, a second door in the bottom of the housing extending to said opening, valve means in said displacement chamber, an air pressure line extending to said displacement chamber, and stabilizing screws in the housing adapted to engage the pile to hold the cage in position around the pile.

5. A marine cage adapted to be partly submerged around a pile comprising a housing open at the top, a displacement chamber in the bottom of said housing, a door in the side of the housing, said housing having an opening in the bottom thereof through which the piling extends, a second door in the bottom of the housing extending to said opening, a valve in the bottom of the displacement chamber, a second valve in the top of the displacement chamber, a pipe rising from the second valve, a rod rising from the first valve, said rod extending through the pipe, operating handles connected to the pipe and rod, and an air hose connected to said pipe whereby air under pressure is admitted to the pipe and thence to the displacement chamber so that the water in the chamber is forced therefrom.
- 10 6. A marine cage adapted to be partly submerged around a pile comprising a housing open at the top, a displacement chamber in the bottom of said housing, a door in the side of the housing, said housing having an opening in the bottom thereof through which the piling extends, a second door in the bottom of the housing extending to said opening, valve means in said displacement chamber, an air pressure line extending to said displacement chamber, said displacement chamber having outwardly flexing walls around the central opening in the housing, and a plastic seal adapted to rest against said walls around the piling whereby the opening in the bottom of the housing is sealed.
- 15 7. A marine cage adapted to be partly submerged around a pile comprising a housing open at the top, a displacement chamber in the bottom of said housing, a door in the side of the housing, said housing having an opening in the bottom thereof through which the piling extends, a second door in the bottom of the housing extending to said opening, valve means in said displacement chamber, an air pressure line extending to said displacement chamber, said displacement chamber having outwardly flexing walls around the central opening in the housing, and a plastic seal adapted to rest against said walls around the piling whereby the opening in the bottom of the housing is sealed, and stabilizing screws in the housing adapted to engage the pile
- 20 8. A marine cage adapted to be partly submerged around a pile comprising a housing open at the top, a displacement chamber in the bottom of said housing, a door in the side of the housing, said housing having an opening in the bottom thereof through which the piling extends, a second door in the bottom of the housing extending to said opening, valve means in said displacement chamber, an air pressure line ex-
- tending to said displacement chamber, said displacement chamber having outwardly flexing walls around the central opening in the housing, and a plastic seal adapted to rest against said walls around the piling whereby the opening in the bottom of the housing is sealed, a plate adapted to closely encircle the pile, said plate fitting over the opening in the bottom of the housing, said seal being adapted to rest on the plate, said valve means in the displacement chamber comprising upper and lower superposed valves, the lower valve opening out of the bottom of the chamber, the upper valve opening into the housing, a tube rising from the upper valve, a rod rising from the lower valve and extending through the tube, and operating handles secured to the upper ends of the tube and rod.
